US0D1066652S

(12) **United States Design Patent** (10) Patent No.: **US D1,066,652 S**
(45) Date of Patent: ** Mar. 11, 2025

(54) **MEDICAL DEVICE CAP**

(71) Applicant: **TISSIUM**, Paris (FR)

(72) Inventors: **Aurélien Delebarre**,
Conflans-Sainte-Honorine (FR); **Simon
Menand**, Latresne (FR); **Estelle Collin**,
Alfortville (FR); **Richard Dent**,
Alfortville (FR)

(73) Assignee: **Tissium**, Paris (FR)

(**) Term: **15 Years**

(21) Appl. No.: **35/517,869**

(22) Filed: **May 10, 2023**

(80) **Hague Agreement Data**

Int. Filing Date: **May 10, 2023**

Int. Reg. No.: **DM/230251**

Int. Reg. Date: **May 10, 2023**

Int. Reg. Pub. Date: **Jul. 21, 2023**
